UNITED STATES PATENT OFFICE.

JOHN S. SCHUMAKER AND LEROY M. GLODELL, OF HARTFORD, CONNECTICUT.

SECTION-INSULATOR.

SPECIFICATION forming part of Letters Patent No. 640,959, dated January 9, 1900.

Application filed June 14, 1899. Serial No. 720,562. (No model.)

To all whom it may concern:

Be it known that we, JOHN S. SCHUMAKER and LEROY M. GLODELL, citizens of the United States of America, and residents of the city 5 and county of Hartford and State of Connecticut, have invented certain new and useful Improvements in Section-Insulators, of which the following is a specification.

This invention relates to section-insulators or "cut-outs" of that class especially adapted for use in connection with overhead conductors of electric railway or trolley systems wherein the separate sections of the conductor are relatively insulated and supplied by 15 "feeders."

The principal object of this invention is to provide a simple, durable, and efficient section-insulator embodying a plurality of under-runs insulated from one another and separated from each other by air-spaces and to so construct and organize the parts of said section-insulator that the same may be readily applied and secured in place between the adjacent ends of the conductors of two adjacent sections and whereby the stress of said conductors will tend to center the under-runs with respect to the central line of the conductors and also increase the effective resistance to strain of the strain-bearing parts of said section-insulator.

A further object of this invention is to furnish a section-insulator for electric conductors comprehending a box-like casing, two strain-bearing end members embodying 35 means whereby the ends of the conductors may be secured thereto and having at their inner ends coöperative wedges supported in the casing for longitudinal movement and insulated from one another and from said casing, and a plurality of under-runs disposed intermediate the two end members and separated from each other and from said end members by air-spaces, substantially as hereinbefore described, and more particularly pointed 45 out in the claims.

The invention consists in certain details of construction and in the combination and organization of the several parts of the section-insulator, as will be hereinafter described and 50 claimed.

In the drawings accompanying and forming

part of this specification, Figure 1 is a side elevation of a section-insulator embodying the present invention, only a portion of the ends of two adjacent section conductors or 55 wires being shown. Fig. 2 is a longitudinal section of the section-insulator, taken on a line corresponding with the dotted lines 2 2 in Fig. 1 and showing the parts below said line; and Fig. 3 is a cross-sectional view of 60 the section-insulator, taken on the dotted line 3 3 in Fig. 1 and showing the parts at the left of said line.

Similar characters indicate like parts in all the figures of the drawings. 65

In the preferred construction and organization thereof (illustrated in the accompanying drawings) the section-insulator as a whole comprises a casing or body portion B, having a substantially central longitudinal opening 4 extending from end to end thereof, the side walls of which are parallel, two stress-bearing end members or castings C and C', respectively, having coacting wedges W and W' at their inner ends, respectively, and also 70 embodying means whereby the ends 5 and 5' of the conductors D and D' may be secured to the end members C and C', and two under-runs E and E', secured to the casing or body portion at opposite sides, respectively, of the 75 center thereof and separated from each other and from the inner ends of the end members by air-spaces 6, 7, and 7', respectively, the wedges of the end member being insulated with respect to each other and with respect 80 to the casing and the two under-runs being also insulated from each other and with respect to said casing, as will be readily understood by reference to Figs. 2 and 3 of the 85 drawings. 90

In Figs. 2 and 3 of the drawings the casing or body portion B of the section-insulator is shown having a substantially square central longitudinal opening, the side walls 8 and 8' of said casing having their inner faces substantially parallel with each other and with the outer faces of said side walls, and in Fig. 2 the casing is shown set with its longitudinal axis oblique to and intersecting a line, as the dotted line 9 9, drawn longitudinally 95 through the center of the end members C and C', and it is desired to here state that the in- 100

vention is not limited to the particular form of casing illustrated in Figs. 1 to 3, inclusive, of the drawings, as certain modifications may be made therein without departure from this 5 invention.

The casing, which is shown of cross-sectionally angular oblong construction, has formed substantially midway of its length and projecting outward from opposite side faces 10 thereof two eyes or loops 10 and 10', respectively, and also has a central strengthening-bead 12 and two end strengthening-beads 13 and 14, respectively. This casing also has 15 extending upward from the central portion of its upper wall a boss 15, which in practice will be internally screw-threaded (said screw-thread not being shown) to receive an insulator whereby the section-insulator may be suspended.

20 The points 16 and 16' of the end members C and C' will in practice be preferably constructed of brass, and for the purpose of decrease in the cost of manufacture will preferably be formed integral with the wedge portions 25 of said end members by casting or welding, and the wedge portions of said members will preferably be formed of cast-iron.

In the organization thereof shown in Fig. 2 of the drawings the adjacent faces of the 30 wedges W and W' are parallel to the central line 9 of the end members and are covered with insulating material, as shown at 17 and 17', and the outer faces of said wedges are disposed obliquely to said central line 9, so 35 that when stress is exerted in opposing directions on the outer ends of the end members by the conductors D and D' the outer faces of the wedges will tightly engage the inner walls of the casing, thus preventing further 40 outward movement of said end members longitudinally of said casing, the inner adjacent walls of said wedges preventing transverse movement and insuring the centering of said wedges transversely of the casing.

45 As a convenient means for securing the ends of the conductors in place on the end members C and C' said members have their opposing side faces grooved at 18 from the points backward and upward to receive and 50 form seats for the conductor ends and are also provided with clips or prongs 19 and 19', respectively, which in practice will be cast integral with the end members and will be bent over and around the ends of the conductor, as shown most clearly in Figs. 1 and 2 of the drawings.

The middle under-runs E and E' are preferably cast integral with box-like casings 20 and 20', respectively, each of which is of a cross-60 sectional shape corresponding to that of the casing or body portion B, and constructed to fit around the bottom and side walls of said casing, and each under-run casing having an outwardly-projecting flange 21 at the upper 65 side edge thereof, which is perforated to receive a screw-bolt, and having at the opposite upper side edge thereof an opening to receive

a prong 22 on a strap 23, which secures the under-run casing in place, said strap having one end perforated to correspond to the perforation in the under-run casing and being secured in place by a screw-bolt 24, extending therethrough and through the flange at the upper end of the under-run casing, as will be readily understood by reference to Fig. 3 of 75 the drawings.

The ends of the conductors will in practice be "sweat" in place after being secured to the end members C and C' by the clips 19 and 19'.

For the purpose of reducing weight and expense the wedges W and W' of the end members will be cored out, and in the form thereof shown in Fig. 3 they are of H shape, each comprising the inner and outer side walls 25 and 25', connected together at its middle portions by a horizontal web 26. It will be obvious, however, that the form of the wedge may be modified within the purview of this 85 invention.

We claim—

1. A section-insulator comprising a casing having an opening extending therethrough from end to end thereof; and two oppositely-disposed end members embodying coacting 95 wedges supported in said casing and also embodying means whereby the ends of the section-conductors may be secured thereto.

2. The combination, in a section-insulator, of a box-like casing; two oppositely-disposed 100 wedges supported for limited movement in said casing and having end portions embodying means for attaching the ends of the section-conductors thereto; a plurality of under-runs disposed between the inner lower ends 105 of the end members and separated from each other and from said end members by air-spaces; and insulation interposed between the under-runs and their supports, and between the wedges and the casing, substantially 110 as described.

3. The combination in a section-insulator of two strain-bearing members having wedges at their inner ends the straight faces of which are in co-operative relation and are separated 115 by insulating material; a casing surrounding and supporting said wedges and having inclined side walls co-operative with the side faces of said wedges, whereby to limit the movement of one wedge relatively to the other; a plurality of under-runs, disposed one at each side the center of the casing and insulated therefrom, the lower portions of said under-runs being in horizontal alignment with the lower portion of the strain-bearing members and being separated from each other, and from said members by air-spaces.

4. A section-insulator embodying a casing having a longitudinal opening therethrough, and two oppositely-disposed wedges, supported in said casing and insulated therefrom, and having end members formed integral with the outer ends thereof; means in connection with the end members for holding the ends of the 125 130

conductors; a plurality of under-runs removably secured to the casing between the inner ends of the end members and separated from each other and from said end members by air-spaces, said under-runs being insulated with respect to said casing.

5. In a section-insulator, the combination of a casing having a cross-sectionally rectangular opening therethrough, which opening is lined with insulating material; two oppositely-disposed coöperative wedges supported in said casing and having at the outer ends thereof, conductor-supporting end members; a prong integral with each end member and adapted

to be bent over to engage the end of the conductor; and one or more under-runs supported between the inner ends of the end members and separated therefrom by air-spaces, and being insulated with respect to the casing and end members.

Signed by us at Hartford, Connecticut, this 7th day of June, A. D. 1899.

JOHN S. SCHUMAKER.
LEROY M. GLODELL.
